UNITED STATES PATENT OFFICE

RUDOLF R. KARICH, OF JAMAICA, NEW YORK, ASSIGNOR TO EBCO MACHINE CORPORATION, OF NEW YORK, N. Y., A CORPORATION OF NEW YORK

COMB FOR TOBACCO FEEDERS

Application filed August 16, 1929. Serial No. 386,250.

This invention relates to combs for tobacco feeders.

A feature of the present invention is the provision of adjustable self-adjusting fingers 5 of a comb for tobacco feeders and particularly in association with drums, rolls and other actuated members provided with carding.

Pursuant to specific embodiments set forth 10 more particularly hereinafter, my comb is applicable in association with the main carding drum of the carding mechanism of a cigarette making machine comprises a casting, usually adjustably supported and a plurality of fingers of the desired number 15 respectively individually self-adjusting and preferably individually resiliently adjustable. Usually the number of fingers corresponds to the number of peripherally related 20 tooth spaces of the carding, and the free end of each finger is outwardly tapered at its terminus and provided with a curved effective face adjacent such tapered portion and brought into frictional engagement with the 25 tobacco shreds filling the tooth spaces, to thereby more effectually attain the regulatory functions of the comb, as will appear more fully hereinafter.

Further features and objects of the invention 30 will be more fully understood from the following detail description of the accompanying drawings, in which

Fig. 1 is a central vertical sectional view 35 illustrating the use of my improved comb in association with the main carding drum of a carding mechanism of a cigarette making machine of the rod-forming type;

Fig. 2 is a detail elevation, on a large scale, 40 of one embodiment of my invention, the cover being broken away in part to show otherwise hidden elements, and

Fig. 3 is a sectional elevation on line 3—3 of Fig. 2.

Fig. 1 is largely diagrammatic in representation, and illustrates a conventional type 45 of hopper 10 and therein enclosed carding mechanism including a main carding drum 11 which is rotated on its horizontal axis 12 in the direction of the arrow 13, and is provided with carding, the teeth 14 of which are

inclined in the direction of its rotation. The drum 15 is a brushing or dressing drum which is rotated, usually intermittently, on its horizontal axis 16 in the direction of the arrow 17. The drum 15 is shown provided with carding the teeth 18 of which are inclined reversely to the direction of its rotation. At 19 is indicated a fan or equivalent usually employed with the dressing or brushing drum, as will be understood. 55

The feed of shredded tobacco charged into the hopper, upon removal of its cover 20, is illustrated by the use of an endless conveyor belt 21, the upper stretch 22 of which is driven in the direction of the arrow 23. 60 65

My improved comb is indicated at 24, the details of which are illustrated and described more fully hereinafter. In this instance of use, my comb functions as a so-called front comb, that is to say, on the downwardly moving side of the main carding drum 11; in such instance of use it is associated with a picker roll 25 which may be rotated in the direction of the indicated arrow 26 for the discharge of the carded tobacco shreds from 70 the tooth spaces of the carding of the main carding drum 11. Such discharge, indicated at 27, may be directly into the chute 28 upon the upper face of the travelling continuous web 29 of cigarette paper, shown 75 80 slidingly supported within the regulation slotted guide plate 30, or such discharge 27 may be upon a regulation endless conveyor belt, which in turn discharges the carded tobacco into such chute, as will be understood 85 by those skilled in the art.

In the co-pending application of William F. Grupe, Serial No. 363,785, filed May 17, 1929, entitled Carding mechanism for cigarette making machines, is illustrated another 90 instance of use of my improved front comb.

As one preferred embodiment of my invention, my front comb includes an angle bar member 31, which is provided with flanges 32, see Fig. 2, at its opposite ends, 95 said flanges being provided with openings for receiving screws 33 or equivalent for adjustable attachment or securement to the side boards of the hopper proper, one, 34, only being indicated in Fig. 2. The casing fur- 100

ther includes a hollow body portion 35, the bottom 35a of which is substantially flat at its under face 35b and open at its posterior side 35c. The face 35d at the anterior termi- 5 minus of the bottom plate 35a is outwardly tapered to conform to and act as a stop for the respective fingers 36.

Each pin 36 is mounted to be articulated about a suitable fulcrum, and as a simple 10 and effective type of articulation each finger 36 is provided with a curved head arranged to be pivotally seated within complementary or other suitable curved seats, as appears more fully hereinafter.

15 The anterior portion 35e of the casing body 35 is provided with a series of arcuate recesses 37 corresponding in number to the comb fingers 36 and serving as a bottom seat and fulcrum of the respective comb fingers.

20 The angle bar member 31 serves to support the casing body portion 35 by means of screws 38 passing through suitable openings in the angle bar member 31 and into tapped openings within the anterior portion 35e.

25 The casing further includes the cover 40 which is preferably removably secured in position by set screws 41. To the under face of the cover 40 is secured by screws 42 the bar 43 having curved fulcrum seats which 30 correspond in number and in complementary register with the respective seats 37 of the anterior casing portion 35e.

35 Preferably, the comb fingers 36 are individually resiliently adjusted, and as a simple embodiment of this feature of my invention, springs 44 are provided individually for the respective comb fingers 36, one end 45 of each spring being secured to its set screw 46, the head of which extends through its 40 screw threaded opening 47 and provided with a slot 48 which is thus disposed to be accessible exteriorly of the casing for application of a screw driver or other suitable tool for individual adjustment.

45 Each spring 44 is preferably of helix formation, its free end being received about and enclosing a lug 49 or equivalent carried by the individual comb fingers 36.

50 Such arrangement effects a simple assembly and disassembly of the comb fingers and provides for ready inspection of the fingers by mere removal of the cover 40. The individual resilient spring affords individual adjustment of the comb fingers arising from 55 wear.

55 Preferably, each comb finger is provided with a downwardly tapered terminal portion 36a and a convex face portion 36b, the latter being brought under resilient pressure by its 60 individual spring into resilient frictional engagement with the layer of carded tobacco shreds indicated at 50 on the main carding drum 11 or other drum or roll provided with carding with which the comb is associated.

65 Appreciating that the average charge of

shredded tobacco comprises from 25% to 40% of so-called "shorts", that is to say, tobacco shreds of relatively short lengths and the remainder in substantially equal proportion of shreds of relatively long and intermediate shred lengths, the layer of the tobacco shreds fed by the back feed belt 21 or equivalent and combed by the combing roll 55, gives rise to variations of density and distribution of shred length within the tooth spaces of the carding of the drum. In such circumstance, with the use of a picker roll, such as the regulation picker roll 25 or the like, it is desirable to discharge the carded tobacco shreds from the carded periphery 70 of the main drum 11 substantially in the order of the tooth spaces—as viewed horizontally—as the pins of the picker roll 25 enter therein upon the conjoint rotation of the picker roll 25 and the downward travel of the carded drum 11.

75 In addition to the above stated variations of shred length, further factors tending to produce inequalities of discharge include the lodging of the relatively long fibers about one or more of the teeth of the carding, the placement of the long fibers in more than one row of the tooth spaces—as viewed peripherally—variations of release from the tooth spaces 80 when encountered by the pins of the picker roll arising from different peripheral speeds of the pins relative to that of the carding drum, different length of picker pin relative to the effective length of the carding teeth 85 etc.

90 I have discovered that with the use of individually tensioned comb fingers, similarly as above set forth, such variations of release and discharge due to different shred lengths 95 of the carded depot upon the carding drum and other factors specified above and otherwise are minimized, and the distribution of the shreds within the tooth spaces of the carding of the carding roll 11 is more uniformly preserved with the use of combs embodying my invention.

100 When the cover 40 is removed for inspection, replacement or adjustment of teeth or other purpose, the removal of the cover effects the removal of the individual springs 115 44, and similarly the replacement of the cover restores the individual springs in proper position relative to the respective comb fingers.

110 It will further be observed that the under face of the bottom 35a serves a retainer to maintain the carded tobacco shreds within the tooth spacing of the carding of the main drum 14 or equivalent; for this purpose if desired, the under face of the bottom may be 120 concaved, corresponding to, or approximately 125 to the effective periphery of the carding teeth.

130 My invention is applicable for combs serving as so-called back combs, that is say, on

the upwardly moving side of a carding drum or equivalent.

Whereas, I have described my invention by reference to specific forms thereof, it will be understood that many changes and modifications may be made without departing from the spirit of the invention.

I claim:—

1. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, and individual fulcrum means for said fingers respectively, said individual fulcrum means being carried by said casing.

2. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, individual fulcrum means for said fingers respectively, and resilient means for tensioning said comb fingers, said individual fulcrum means being carried by said casing.

3. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, individual fulcrum means for said fingers respectively, and individual resilient means for individually tensioning said comb fingers, said individual fulcrum means being carried by said casing.

4. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, individual fulcrum means for said fingers respectively, a cover for said casing, and tensioning means opposed between said cover and said fingers for resiliently biasing said comb fingers, said individual fulcrum means being carried by said casing.

5. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, individual ful-

crum means for said fingers respectively, a cover for said casing, and resilient means carried by said cover for resiliently biasing said comb fingers, said individual fulcrum means being carried by said casing.

6. A tobacco feeder comprising in combination, a carding drum of substantially cylindrical contour, sets of rows of carding teeth arranged about the cylindrical surface of said carding drum, and comb means for said sets of rows of carding teeth, said comb means comprising a casing, a plurality of individual comb fingers, individual fulcrum means for said fingers respectively, a cover for said casing, and individual springs carried by said cover in register with said comb fingers for resiliently biasing said comb fingers independently, said individual fulcrum means being carried by said casing.

7. A tobacco feeder comprising in combination, a carding drum of substantially cylindrical contour, sets of rows of carding teeth arranged about the cylindrical surface of said carding drum, and comb means for said sets of rows of carding teeth, said comb means comprising a hollow casing provided with a plurality of fulcrum seats, a plurality of individual comb fingers having arcuate portions received within said fulcrum seats, and a cover for enclosing said fingers within said casing in fulcrum relation with said fulcrum seats respectively.

8. A tobacco feeder comprising in combination, a carding drum of substantially cylindrical contour, sets of rows of carding teeth arranged about the cylindrical surface of said carding drum, and comb means for said sets of rows of carding teeth, said comb means comprising a hollow casing provided with a plurality of fulcrum seats, a plurality of individual comb fingers having arcuate portions received within said fulcrum seats, a cover, complementary fulcrum seats carried by said cover, and means for removably positioning said cover on said casing.

9. A tobacco feeder comprising in combination, a carding drum of substantially cylindrical contour, sets of rows of carding teeth arranged about the cylindrical surface of said carding drum, and comb means for said sets of rows of carding teeth, said comb means comprising a hollow casing provided with a plurality of fulcrum seats, a plurality of individual comb fingers having arcuate portions received within said fulcrum seats, a cover, complementary fulcrum seats carried by said cover, resilient means for said comb fingers carried by said cover, and means for removably positioning said cover on said casing.

10. A tobacco feeder comprising in combination, a carding drum of substantially cylindrical contour, sets of rows of carding teeth arranged about the cylindrical surface of said carding drum, and comb means for

said sets of rows of carding teeth, said comb means comprising a hollow casing provided with a plurality of fulcrum seats, a plurality of individual comb fingers having arcuate portions received within said fulcrum seats, a cover, complementary fulcrum seats carried by said cover, individual resilient means for said comb fingers carried by said cover, and means for removably positioning said cover on said casing.

In testimony whereof I have signed this specification this 8th day of July, 1929.

RUDOLF R. KARICH.
